United States Patent Office.

HARRISON EATON, OF AMHERST, NEW HAMPSHIRE.

Design No. 3,155, dated August 11, 1868.

DESIGN FOR COOKING-STOVE.

The Schedule referred to in these Letters Patent and making part of the same.

TO ALL PERSONS TO WHOM THESE PRESENTS MAY COME:

Be it known that I, HARRISON EATON, of Amherst, in the county of Hillsboro, and State of New Hampshire, have invented or produced a new ornamental Design for a Cooking-Stove; and I do hereby declare the same to be fully represented in the accompanying drawings, of which—

Figure 1 is a perspective view, illustrative of the front and side of it.

Figure 2 is a perspective view of the rear and other side of it.

Both sides of the stove are alike in form and ornamentation, except that in one of them is a small door to the fireplace, with a hearth underneath it, as shown in fig. 2.

The main hearth *a* has an ornamental cover, as shown at *b*, over which are the main fireplace-doors formed with register-openings, and with mouldings, in manner as represented.

Each of the oven-doors *c* has mouldings on its edges, and a sunken panel containing an ornamental shield supporting a rosette in bas-relief, the edges of the panel and the shield being dentilated. The top, bottom, and hearth of the stove have mouldings on their edges. The back has three arched panels. The sides are panelled, and the corners of the body are formed with pilasters, the whole being as represented in the aforesaid figures.

I claim the ornamental design for a cook-stove, as represented, and hereinbefore described.

HARRISON EATON.
